(57) **CLAIM**

The ornamental design for an adjustable woodworking rule, as shown and described.

DESCRIPTION

FIG. 1 is a front, top, left side, isometric perspective view of an adjustable woodworking rule in accordance with my design, shown in a first position;

FIG. 2 is a front elevation view thereof;

FIG. 3 is a rear elevation view thereof;

FIG. 4 is a left side elevation view thereof;

FIG. 5 is a right side elevation view thereof;

FIG. 6 is top plan view thereof;

FIG. 7 is a bottom plan view thereof;

FIG. 8 is a cross-section of the adjustable woodworking rule shown in the direction of line 8-8 of FIG.2;

FIG. 9 is a front elevation view of the adjustable woodworking rule shown in a second position;

FIG. 10 is a rear elevation view thereof;

FIG. 11 is a front elevation view of the adjustable woodworking rule shown in a third position; and,

FIG. 12 is a rear elevation view thereof.

The dash-dash broken lines illustrate portions of the adjustable woodworking rule which form no part of the claimed design.

The dot-dot-dash broken lines depict boundaries to the claim and form no part of the claimed design.

1 Claim, 10 Drawing Sheets
